UNITED STATES PATENT OFFICE.

WILTON S. SCHUYLER, OF SAVANNAH, MISSOURI.

FIRE-ALARM-BELL RINGER.

1,260,461.

Specification of Letters Patent. Patented Mar. 26, 1918.

Application filed July 7, 1916. Serial No. 108,038.

To all whom it may concern:

Be it known that I, WILTON S. SCHUYLER, a citizen of the United States, and a resident of the city of Savannah, in the county of

5 Andrew and State of Missouri, have invented a certain new and useful Improvement in Fire-Alarm-Bell Ringers; and I do hereby declare that the following description of my said invention, taken in connection with the accompanying sheets of drawings, forms a full, clear, and exact specification, which will enable others skilled in the art to which it appertains to make and use the same.

10 15 My invention relates generally to improvements in a fire alarm bell ringer and it consists, essentially, in the novel and peculiar combination of parts and details of construction, as hereinafter first fully set forth and described and then pointed out in the claims.

20 25 The object of this invention is the production of an efficient and serviceable mechanically operated mechanism for ringing fire alarms in the smaller cities and other places where a fire alarm bell is in use and which is generally manually operated. My invention includes mechanism whereby the striking of the bell is accomplished by mechanical means and whereby the bell may be 30 35 struck by continuous blows, or at longer and shorter intervals of time as the case may be, so that stations, sections, wards or particular places from which a fire alarm is sent in, may be indicated by a stroke or a succession 40 45 of strokes, followed by an interval of silence and further strokes, in the manner generally employed for sounding a fire alarm.

50 55 In the drawings already referred to which disclose the preferred embodiment of my invention and which illustrates the same quite fully, Figure 1 is an elevation of the striking mechanism in normal position. Fig. 2 is a similar view showing the positions of the parts at the moment when the bell striking mechanism is being engaged for operation. Fig. 3 is a sectional view of the mechanism employed for operating the bell striking mechanism. Fig. 4 is an enlarged view, in section, on line 4-4 of Fig. 3. Fig. 5 is an enlarged view of mechanism employed for automatically silencing the bell striking mechanism, during part of the operation. Fig. 6 is a diagrammatic plan illustrating the disposition of the bell striking mechanism. Fig. 7 is a side elevation of the bell-striking mechanism showing the parts of

this mechanism at the moment when the bell striking hammer is being released, the solenoid shown in Figs. 1, 2 and 5 being omitted.

Referring to Fig. 6, A, indicates a fire 60 alarm bell suspended from the usual head or yoke B having trunnions, 12, on which the bell may be swung. C indicates a series of bell-striking hammers arranged angularly to each other, and D designates the bell- 65 striking mechanism as an entirety.

In practice I locate, preferably, two of these bell striking mechanism, as shown in Fig. 6, whereby the bell A may be swung in the usual manner without touching the hammers or interfering with the bell striking mechanism in any manner.

These bell striking mechanisms are alike in construction so that describing the same in a singular number will be sufficient for a 75 clear understanding of this invention. Each bell striking mechanism comprises a standard E located upon a suitable support E'. The upper extremity of this standard, which is preferably cross-shaped in transverse section, is bifurcated at 13; and in this fork there is pivoted, on a bolt 14, the handle or shank 15 of the hammer C. This shank 15 has an extension 16, which is bifurcated or slotted as shown at 17, Fig. 6, in which slot 80 85 there is movably arranged a push-and-pull rod 18, of peculiar construction. This rod 18 is pivotally connected to the standard E by a link G, having a fork 19 at one end engaging said pull-rod 18 by a pivot bolt 20, 90 and a further fork 21, at the opposing end engaging the web 22, by a pivotal bolt 23.

The fork 19 on the link G is engaged by a connecting member 24 to which a so-called double eye 25 is pivoted, which double eye 95 receives operating rod 26, hereinafter to be referred to.

The pull rod 18 has, approximately medially, a sidewise projecting hook 27 and its upper extremity is curved at 28 and it has 100 a further curved terminal 29, as will be further on referred to.

Near the pivotal point 14 of the hammer shank there is pivotally connected, by a bolt 30, a bar 31, the extremity of which is fitted 105 with a roller 32, which roller contacts with the curved portion 28 of the pull rod 18; and this bar 31 is movably connected to the shank portion 15^a, of the hammer handle by a rod 33, having locking nuts 34.

110 To the pivotal bolt 23 that connects the link G to the standard E, and at both sides

of the forked end 21 of said link, there are pivoted angle irons 35, Fig. 7, and at a suitable distance above the pivot bolt 20 there are further angle irons 36, pivotally connected to the pull rod 18, one on each side thereof, are spiral springs 37 connecting the respective angle irons. There are preferably two of these springs so that should one of these springs break, there will still be one left to perform the function of pulling the pull rod 18 toward the standard E.

At a proper distance from the pivot 14 of the hammer handle, there are suspended angle irons 38, one on each side of the shank 15, and to these angle irons are secured coil springs 39, the lower ends of which are hitched to the base plate 40 of the standard E.

Near the upper end of the standard E 20 there is a sidewise extending bracket 41, to which bracket there is secured a clamp 42, by which a substantial blade spring 43 is secured to said bracket. The object of this latter spring is to support the hammer C 25 and keep it normally away from the rim of the bell B and also to prevent the hammer from repeating a stroke when once delivered by the rebounding thereof, while the object of the two springs 39 is to reinforce the 30 stroke of the hammer by imparting increased velocity thereto when descending to deliver a blow.

The hammer may be operated manually by lifting and pulling the rod 26 which actuates the pulling lever 18, but when desired, power-operated mechanism may be installed to manipulate this rod 18, and in the preferred embodiment of my invention, I provide an electric or other motor H, Figs. 3 40 and 4, the shaft 44 of which carries, preferably, a worm 45 engaging a worm wheel 46 mounted in a suitable gear case 49, said worm wheel rotating loosely on a shaft 47. This shaft has at each of its extremities a 45 crank 48; and in the gear case 49 adjacent the worm wheel and secured to shaft 47, there is a fixed ratchet wheel 50, Fig. 4, which is engaged by a pawl 51 pivotally connected to said worm wheel, whereby the 50 rotation of the crank shaft 47 is effected by the ratchet wheel 50 acting on the pawl 51, the rotation being in one direction only.

One of the cranks 48 connects to one, and the other crank to the other of the two bell 55 striking devices, and these cranks are opposing each other so that the strokes are given at equal intervals, as will be readily comprehended.

In operation, when the pull rod 18 is 60 lifted the upper end thereof will slide upwardly in the slot 17 at the end of the hammer handle 16, until the barb or hook 27 thereon has passed a bolt or pin 52, in the slotted aperture 17, when, by the contraction 65 of the springs 37 acting upon the pull rod

18, the upper end of the pull rod is drawn toward and caused to engage this pin 52.

Now, when the rod 26 is pulled down, the hammer C is lifted until the roller 32 on the bar 31 engages the curved portion 28 70 and pushes the upper end of the pull rod 18 away from the pin 52, thereby liberating the hammer C and causing it to drop, assisted by the springs 39, and to strike the bell B with a forcible and quick blow. This 75 operation is repeated as long as the motor H is operating; but in order to cause a cessation of blows at predetermined intervals, as will hereinafter appear, I provide means for preventing the barb or hook 27 from engaging the pin 52, and I prefer for this purpose the solenoid device I have shown in detail in Fig. 5. Thus on the pull rod 18, below the hook 27, I provide a solenoid 53 of usual design, the core or bar 54 of which 80 has a rod-extension 55, to which is secured a box-shaped member 56, which latter member is adapted to close the notch or gap 57, Fig. 1, below the hook 27, and thereby prevent the hook from catching hold of the pin 52. 85 Normally the solenoid not being energized by an electric current from any source of electric energy, such as the battery I, the core 54 will be moved down together with the box shaped member 56, as illustrated in 90 Fig. 1, but as soon as the solenoid is electrically excited, the core will immediately rise and thus cause the member 56 to close the gap 57. In order to render the solenoid 95 very effective, I counterbalance, in part, the weight of the bar 54 and its superimposed parts, by a weight 58, connected to the bar 54 by a very fine chain 59, passing over a guide sheave or pulley 60. And in order to cause intermittent operation of this solenoid 100 mechanism, I introduce a push button or switch 61, Fig. 2, into the conductor or lead 63, from the battery to the magnet, which switch may be operated manually, or by mechanical means, not shown. In the conductor 64, to the electric motor H, I also interpose a switch 62 which may be operated 105 manually or mechanically as desired.

Attention is now directed to the means whereby the vertically reciprocating rod 18 110 is caused to disengage its hook from the hammer handle toward the end of the downward movement of said push-and-pull rod 18, which disengagement is effected by the pivotal bar 31. This bar has the screw-threaded adjusting rod 33 pivoted to the hammer handle portion 15^a, and it is provided with adjusting nuts 34, whereby said bar 31 may be moved toward and from the hammer handle 15^a. When moved toward 115 the latter member the disengagement will be effected sooner than when the bar is moved farther away therefrom. It will be noticed that this bar 31 moves with the hammer handle, and that when the mechanism is in 120 125 130

normal position shown in Fig. 1, the free end of the bar 31 is at some distance from the reciprocating rod 18. When this rod has reached its limit of upward movement 5 and its hook 27 has engaged the pin 52, and the reciprocating rod 18 then commences its downward movement together with the hammer handle 15^a, the roller 32 approaches the curved portion 28 and contacting therewith, will, while descending, push the upper end of the rod 18 away from the pin 52 and thus free the hammer handle and to cause the hammer to drop and strike the bell. By thus making the bar 31 adjustable, I am enabled to vary the "lift" of 10 the hammer and thereby increase or diminish the force of the blow of the hammer accordingly.

It will be further noticed that the upward movement of the hammer commences with the downward movement of the push-and-pull rod, but that the liberation of the hammer depends upon the position of the bar 31, and not upon the extent or range of the 25 downward movement of said reciprocating rod 18, which in all cases remains constant, and is governed by the throw of the cranks 48 on the hammer operating mechanism.

In smaller towns and villages where a 30 fire alarm is given by a continuous ringing of the fire bell without intermissions, I dispense with the mechanism including the solenoid or magnet, and the gap-closing means, which will cheapen the cost of installation to some extent, and will answer all practical purposes under prevailing conditions. And in this connection I desire to state that while I have heretofore mentioned the stroke of the hammer in the singular 40 number, and while they are, in fact, single strokes, these strokes follow one another in such rapid succession, each hammer giving generally from one to two blows per second, the alarm given is actually in the nature of 45 a tolling of an alarm, which is sufficiently loud to wake up the sleeping people of a town during the night.

Assuming that there are a number of stations in a town from which a fire alarm may 50 be turned in, and assuming that an alarm is turned in from, say, Station No. 3, an alarm would be given for, say, three seconds, an interval of silence of, say, three seconds, following this a further alarm of 55 three seconds followed by a silence of three seconds, another alarm of three seconds, and then a silence of a much longer duration, after which the performance is repeated *ad libitum*, thus indicating by the three successive 60 alarms that the fire alarm came from Station No. 3.

I have heretofore described this invention and my preferred embodiment thereof, with considerable minuteness, but I desire it to 65 be understood that many of the details of

construction may be changed by persons skilled in the art to which my said invention appertains without departing from the scope thereof, as defined in the subjoined claims.

Having thus fully described this invention I claim as new and desire to secure to myself the following:—

1. In an apparatus of the nature described, a bell, mechanism for striking said bell, including a hammer, said hammer being located, and constructed to strike the bell on the exterior thereof, means for continuously operating said striking mechanism, means constructed to prevent the said 70 striking mechanism from striking said bell, means for supporting said hammer normally free from said bell, and means connected to said hammer for varying the distance through which said hammer is lifted. 75

2. In an apparatus of the nature described, the combination, of a bell, a hammer, said hammer being located, and constructed to strike the bell on the exterior thereof, electrically operated mechanism for actuating said hammer, electrically operated mechanism constructed to prevent said hammer from striking said bell while the mechanism for actuating said hammer is operating, said means for preventing the bell from 90 being struck being attached to said bell striking mechanism, and means connected to said hammer for varying the distance through which said hammer is lifted. 95

3. In a device of the type described, a bell, a standard, a hammer pivotally connected to said standard, a push-and-pull rod, means on said push-and-pull rod constructed to engage said hammer in its upward movement, and means constructed to 100 disengage said push-and-pull rod from said hammer toward the termination of the downward movement of said push-and-pull rod. 105

4. In a device of the type described, a bell, a standard, a hammer having a handle pivotally connected to said standard, a push-and-pull rod, a link connecting said push-and-pull rod to said standard, a hook on 110 said push-and-pull rod, a pin on said hammer handle, a spring connected to said push-and-pull rod constructed to draw said latter rod toward said pin to cause said hook to engage said pin at the upstroke of said rod and means constructed to disengage said 115 hook from said pin near the termination of the downward stroke of said push-and-pull rod. 120

5. In a device of the type described, the combination of a bell, a hammer having a 125 handle, a standard to which said handle is pivoted, an extension on said hammer handle, said extension being slotted, a vertically reciprocating rod, the upper terminal being constructed to slide in said slot, said 130

rod being provided with a hook, a link connecting said rod to said standard, a spring constructed to pull said rod toward said standard, means in the aforesaid slot where-
5 with said hook is constructed to engage said hammer handle, and means connected to said hammer handle constructed to disconnect said hook from said hammer handle during the downward movement of said re-
10 ciprocating rod.

6. In a device of the type described, the combination of a bell, a hammer having a handle, a standard to which said handle is pivoted, an extension on said hammer handle, said extension being slotted, a vertically reciprocating rod, the upper terminal being constructed to slide in said slot, said rod being provided with a hook, a link connecting said rod to said standard, a spring con-
15 structed to pull said rod toward said stand-
ard, means in the aforesaid slot wherewith said hook is constructed to engage said hammer handle, means connected to said hammer handle constructed to disconnect said
20 hook from said hammer handle during the downward movement of said reciprocating rod and means constructed to prevent said hook from engaging said hammer handle while said rod is operating.

30 7. In a device of the type described, the combination of a bell, a hammer having a handle, a standard to which said handle is pivoted, an extension on said hammer handle, said extension being slotted, a vertically reciprocating rod, the upper terminal being constructed to slide in said slot, said rod being provided with a hook, a link connecting said rod to said standard, a spring con-
35 structed to pull said rod toward said stand-
ard, means in the aforesaid slot wherewith said hook is constructed to engage said ham-
mer handle, means connected to said ham-
mer handle constructed to disconnect said
40 hook from said hammer handle during the
downward movement of said reciprocating
rod and means constructed to prevent said
hook from engaging said hammer handle
while said rod is operating, said means in-
cluding electrically operated devices.

45 8. In a device of the type described, the combination of a bell, a hammer having a handle, a standard to which said handle is pivoted, an extension on said hammer handle, said extension being slotted, a verti-
50 cally reciprocating rod, the upper terminal being constructed to slide in said slot, said rod being provided with a hook, a link con-
necting said rod to said standard, a spring con-
structed to pull said rod toward said
55 standard, means in the aforesaid slot where-
with said hook is constructed to engage said

65 hammer handle, means connected to said hammer handle constructed to disconnect said hook from said hammer handle during the downward movement of said reciprocating rod and means constructed to prevent said hook from engaging said hammer handle while said rod is operating, said means including electrically operated devices, and said means including a solenoid, said sole-
70 noid being connected to a source of electric energy.

75 9. In a device of the type described, the combination of a bell, a pair of hammers located at the side of said bell, said ham-
mers being constructed to strike said bell on the outer surface thereof, mechanisms for pivotally retaining said hammers, said mechanisms being angularly disposed with respect to each other, and power-operative 80 means constructed to actuate said hammers, said power operating means including a single motor located between, and opera-
tively connected to, the two bell-striking mechanisms, said bell-striking mechanisms 85 being constructed to strike said bell alter-
nately.

90 10. In a device of the type described, the combination of a bell, a pair of hammers located at the side of said bell, mechanisms 90 for pivotally retaining said hammers, said mechanisms being angularly disposed with respect to each other, and power-operative means constructed to actuate said hammers, said power operative means being located 95 between said mechanisms for pivotally re-
taining said hammers, there being means on said power operated means constructed to prevent said hammers from striking while the power-operated means are operating 100 said hammers being constructed to strike said bell alternately.

105 11. In a device of the type described, the combination of a bell, a pair of hammers located at the side of said bell, mechanisms for pivotally retaining said hammers, said mechanisms being angularly disposed with respect to each other, and power-operative means constructed to actuate said hammers, there being electrically actuated means on 110 said power operative means constructed to prevent said hammers from striking while the power-operative means are operating, said hammers being constructed to strike said bell alternately, said power operative 115 means including reciprocating rods, said electrically actuated means being located on said rods.

120 In testimony that I claim the foregoing as my invention, I have hereunto set my hand.

WILTON S. SCHUYLER.
